ERASTUS E. WINKLEY, OF LYNN, MASSACHUSETTS.

EQUILIBRATING MECHANISM FOR FLYING MACHINES.

Application filed June 25, 1918. Serial No. 241,860.

To all whom it may concern:

Be it known that I, ERASTUS E. WINKLEY, a citizen of the United States, residing at Lynn, in the county of Essex and State of Massachusetts, have invented certain new and useful Improvements in Equilibrating Mechanism for Flying Machines; and I do hereby declare the following to be a full, clear, and exact description of the invention, such as will enable others skilled in the art to which it appertains to make and use the same.

The present invention relates to machines, and more particularly to equilibrating mechanisms for maintaining members or devices in a condition of substantial equilibrium.

The invention will be hereinafter described for the sake of concreteness in connection with a flying machine. It will be clear, however, that the invention is of broader applicability than to flying machines alone and that any one of many other types of machines might have been chosen equally well for illustrative purposes.

The operation of machines in general, and of equilibrating mechanisms in particular, is defective in that the moving parts do not respond readily to the action of the operative forces. This is caused by a sluggishness of action due to well known, inherent time lags. Thus, it has been proposed to control both the longitudinal and the lateral equilibrium or stability of a flying

machine by a pendulum so connected with the guiding devices of the machine that when either the longitudinal or lateral relation between the pendulum and the flying machine is changed by a tipping of the machine, the pendulum acts upon the guiding devices to restore the machine to its normal condition of equilibrium. A practical objection to the employment of a pendulum directly connected with the guiding devices of a flying machine lies in the fact that the pendulum cannot act upon the guiding devices to turn the latter to restore the machine to its normal condition until the angular relation between the pendulum and the flying machine is changed. By reason of the fact that the pendulum is a relatively heavy body, thereby exerting considerable friction upon its bearing, and the turning of the guiding devices requires that a con-

tendency of the pendulum is to move with the flying machine and remain in fixed angular relation therewith, so that an appreciable period of time elapses before gravity, in acting upon the pendulum, can bring its vertical axis perpendicular, thereby changing the angular relation between the vertical axis of the pendulum and either the longitudinal or lateral axis of the flying machine. This time interval or lag is present not only when the equilibrium of the machine is controlled by a pendulum, but irrespective of the nature of the controlling mechanism. If the machine be controlled, not by a pendulum, but by pneumatically operating devices, for example, the time lag will be caused by the lag of the valves. If the machine is controlled by a clutch, the time lag will be found during the period when the clutch parts are moved relatively toward each other into operative relation. During this time interval or lag, the guiding devices, of course, do not act upon the machine, so that there is no actual restoring movement of the machine toward equilibrium until after the time interval has elapsed. The result is that when the equilibrium or stability of the flying machine is disturbed either longitudinally or laterally, its tendency is to tip still farther in either direction. The ultimate result is either that the flying machine pursues an undulating course or else that it is completely overbalanced and falls.

It is, therefore, an object of the present invention to reduce the time lags incident to the operation of machines, and particularly those incident to the operation of equilibrating mechanisms.

To the attainment of this end, a feature of the invention resides in initially moving the guiding devices in response to a force independent of the normal restoring force and which acts before the normal force can act. By the time that the normal restoring force commences to act, therefore, some force has already been exerted upon the machine to compensate for the time interval or lag during which the normal restoring means is initially ineffective.

In the specific embodiment of the invention, which is herein illustrated and described, an equilibrating mechanism is provided for a flying machine in which a relatively heavy pendulum is used to act upon

the guiding devices to restore the flying machine to its condition of equilibrium, and an auxiliary pendulum, which is of relatively light weight, is employed to perform no other function than to throw other devices into operation to effect an immediate or primary restoring movement of the guiding devices. This primary movement of the guiding devices acts to partially restore the flying machine to its condition of equilibrium, thus compensating for the time lag of the heavy pendulum. Incidentally, the auxiliary pendulum serves to connect the main pendulum with the guiding devices, so that in case the flying machine is unbalanced a substantial amount, the guiding devices will be turned accordingly to effect a greater restoring tendency than when they are first turned through the medium of the auxiliary pendulum alone.

By reason of the fact that the pendulum for controlling the guiding devices is a relatively heavy body and is mounted to swing freely, its inertia prevents it from moving forwardly simultaneously with the flying machine when the machine is getting under way. This results in a change in the angular relation between the pendulum and the flying machine so that the guiding devices are acted upon at a time when they should not be moved, namely, when the flying machine is proceeding upon a level course. Another object of the present invention is to provide an equilibrating mechanism, in which the guiding devices are controlled by a pendulum, with a device which acts to hold the pendulum relatively immovable with respect to the flying machine until the flying machine attains a predetermined speed, whereupon the device is disconnected from the pendulum to permit the latter to swing freely.

These objects of the invention and such other objects as are incidental thereto are embodied in the equilibrating mechanism for flying machines hereinafter described and particularly pointed out in the appended claims.

The invention is illustrated in the accompanying drawings in which Figure 1 is a diagrammatic vertical longitudinal section of the fuselage of a flying machine showing the application thereto of the equilibrating mechanism; Fig. 2 is a section taken on the line 2-2 of Fig. 1; Fig. 3 is a view similar to Fig. 1 showing the action of the auxiliary pendulum upon the horizontal rudder when the longitudinal stability of the machine has been disturbed; Fig. 4 is a top plan of the parts shown in the preceding figures; Fig. 5 is a view similar to Fig. 3 showing the position of the parts when the longitudinal stability of the flying machine has been disturbed to a considerable extent; Fig. 6 is a rear elevation partly in section

of a flying machine showing the control of the lateral rudders or ailerons by the equilibrating mechanism and showing also the device for holding the pendulum fast at the beginning of the flight of the machine; Fig. 7 is a horizontal section between the wing planes of Fig. 6, with the central portion of the lower plane broken away; Fig. 8 is a detail perspective of one of the levers for operating the ailerons; Fig. 9 is a vertical longitudinal section through the middle of the parts shown in Figs. 6 and 7; Fig. 10 is a perspective of the main pendulum and associated parts showing the manner of mounting them; Fig. 11 is a group detail perspective of certain of the parts shown in Fig. 10; Figs. 12 and 13 are respectively a transverse and a longitudinal vertical section of the parts shown in Fig. 10; and Fig. 14 is a diagrammatic view showing the main pendulum as a bomb filled with explosive mixture and projectiles and connected with a detonating mechanism.

The equilibrating mechanism of the present invention as illustrated in the accompanying drawings is adapted to control the longitudinal stability of the flying machine to which it is applied through the usual horizontal rudder, and the lateral stability of the flying machine through the usual lateral rudders or ailerons. For convenience of illustration and also of description, the equilibrating mechanism will first be described in its control upon the longitudinal stability of the flying machine and then in its control upon the lateral stability of the flying machine; after which it will be pointed out how the main pendulum is adapted to serve as a bomb or chamber for containing a charge of explosive mixture, which when the flying machine has reached a predetermined point is discharged by a detonating mechanism.

Referring particularly to Figs. 1 to 5 inclusive, it will be seen that the equilibrating mechanism is provided with a main pendulum 15 which is mounted for swinging movements longitudinally or in fore and aft directions on a pivot pin 17 fixed in the fuselage 18 of the flying machine. The longitudinal equilibrium or stability of the flying machine is controlled through the usual horizontally disposed rudder or guiding device 19 pivoted on the transverse pin 20 at the rear of the machine. Depending downwardly from the rudder 19 and in fixed relation therewith is an arm 21, pivoted to the lower end of which is a link or rod 22 pivotally connected at its forward end with the upright arm 24 of a three-arm lever 25 mounted to turn on a transverse pivot pin 23. The lever 25 and the rod 22 constitute guiding device operating means. On the outer end of the rear horizontal arm 26 of the lever 25 is fixed an armature 27 and on

the outer end of the front horizontal arm 28 of the lever 25 is fixed an armature 29. Turning movements are imparted to the lever 25 to actuate the rudder 19 to effect a change in the angle of flight of the flying machine, when the armatures 27 and 29 are acted upon by the magnets or solenoids 30 and 31 which are supported respectively on shelves 40 and 41 projecting laterally from the pendulum 15. The magnets are energized by a battery 32. The battery 32 is permitted to energize either magnet when either of two normally open circuits connecting the battery with the magnets is closed by an auxiliary pendulum 16 making a contact with either the terminal 34 or the terminal 35. This occurs when the longitudinal stability of the flying machine has been disturbed by a depression of either the front or the rear end of the machine, so as to change the angular relation of the auxiliary pendulum and the machine. The auxiliary pendulum 16 is mounted for swinging movements in fore and aft directions on the pivot pin 37 fixed in the fuselage of the flying machine. When the rear end of the flying machine is depressed, as shown in Fig. 8, the auxiliary pendulum makes a contact with the terminal 35, thereby closing the circuit 38 and energizing the magnet 31. This draws the arm 28 toward the magnet 31, turns the lever 25 anti-clockwise and so swings the horizontal rudder 19 in a direction to decrease the angle of incidence of the machine. When the front end of the machine is depressed, then the auxiliary pendulum contacts with the terminal 34, closing the circuit 39 and thereby energizing the magnet 30 to pull the arm 26 toward itself. This turns the lever 25 clockwise and so swings the rudder 19 in a direction to lift the nose of the machine. Until the longitudinal equilibrium or stability of the machine has been disturbed sufficiently to cause the auxiliary pendulum to contact with either terminal 34 or 35, the main pendulum is mechanically disconnected from the horizontal rudder 19 and has no effect upon it. When, however, the flying machine has been tipped longitudinally sufficiently to cause the auxiliary pendulum to contact with either terminal, then the main pendulum is mechanically connected with the rudder 19 through the armature arms 26 and 28 so that it will thereafter control the amount of movement to be imparted to the rudder 19 to restore the machine to its normal condition of longitudinal equilibrium. The movement of the rudder 19 is proportionate to the amount the flying machine is tipped, that is to say, it is proportionate to the amount of angular change between the pendulum and the flying machine. This is made clear from a consideration of Fig. 5 where the circle in dot and dash lines repre-

sents the normal position of the main pendulum with respect to the fuselage of the flying machine, and the circle in cross section represents the position the main pendulum naturally assumes with its vertical axis perpendicular to the horizon after the machine has been tipped for an appreciable amount of time. The main pendulum and the horizontal arm 28 of the three-armed lever 25 being rigidly connected through the magnet 31, the rudder 19 is, of course, turned proportionately to the amount of angular change between the vertical axis of the main pendulum and the longitudinal axis of the flying machine. If the bow of the machine were depressed rather than the rear portion thereof, the rudder 19 would be turned in a reverse direction, that is, it would be turned to a negative and not to a positive angle, because of the fact that the auxiliary pendulum would then be in contact with the terminal 34 and the arm 26 of the lever 25 would then be in contact with the magnet 30.

Owing to the relatively great weight of the main pendulum, the friction necessarily thereby imposed upon the pivot pin 17 and the amount of force necessary to turn the rudder 19, the main pendulum will not remain with its vertical axis perpendicular when the flying machine is tilted fore and aft, but will tend to move in the direction in which the machine is tilted. That is to say, if the nose of the machine is tilted upwardly owing to the depression of the rear end, the pendulum will tend to and actually will swing forwardly and upwardly with the machine a certain amount, and so also when, on the other hand, the nose of the machine is depressed thereby lifting the rear end thereof the main pendulum will swing rearwardly and upwardly; in other words, the pendulum tends to maintain a fixed angular relation with the flying machine. This has been demonstrated by a series of experiments. Of course, when the main pendulum swings in either direction with the upward movement of either the fore or aft part of the flying machine, gravity immediately acts upon the pendulum so as to restore the vertical axis thereof in a perpendicular position. It is this pull of gravity upon the main pendulum that causes the horizontal rudder to turn in a direction to restore the flying machine to its longitudinal equilibrium. If the amount of disturbance of the flying machine is not very great, it may not be a serious matter that the rudder is not acted upon immediately by the pendulum to restore the equilibrium of the flying machine. If, however, the amount of disturbance is considerable, it may be a very serious matter that the rudder is not acted upon immediately by the pendulum to tend to right the flying machine. To secure an immediate or primary

restoring movement of the rudder, thus compensating for the time lag of the main pendulum, the auxiliary pendulum is provided to act through intermediary devices to immediately turn the rudder in a direction to tend to restore the equilibrium of the machine upon a disturbance thereof. This auxiliary pendulum is never at any time mechanically connected with the rudder and so the amount of friction on the pivot pin on which the auxiliary pendulum hangs is, therefore, reduced to a minimum; accordingly, the auxiliary pendulum is free to change its angular relation with the flying machine until the auxiliary pendulum contacts with either terminal 34 or 35.

The control of the lateral equilibrium or stability of the flying machine by the equilibrating mechanism is most fully illustrated in Figs. 6 to 9 inclusive. As in the case of the control of the longitudinal equilibrium of the flying machine, the auxiliary pendulum is employed to effect a primary restoring movement of the guiding devices or rudders for controlling the lateral stability of the machine, and thereafter the main pendulum effects the requisite turning movement of the lateral rudders to restore the machine to its condition of lateral equilibrium or stability. These lateral rudders or ailerons of the flying machine are attached to the outer rear edges of the sustaining wing planes 45 and 46 of the machine and comprise two upper ailerons 47 and 48 pivoted to the upper wing plane 45 and two lower ailerons 49 and 50 pivoted to the lower wing plane 46. The upper and lower ailerons are joined together to move in unison by means of vertically disposed rods 52. The ailerons are moved so as to restore the flying machine to lateral equilibrium by means of transversely disposed rods 53 and 54. The rod 53 is connected at its left hand end with an arm 55 of a three-armed lever 56 pivoted on a standard or upright 57 fixed on the left hand end of the lower wing plane 46, and is connected at its right hand end with the arm 58 of a three-armed lever 59 pivoted on a standard or upright 60 fixed on the right hand end of the lower wing plane. The rod 54 is connected at its left hand end with the arm 62 of the lever 56 and is connected at its right hand end with the arm 63 of the lever 59. The third arm 64 of the lever 56 is connected by a universal joint with a link 65 pivotally connected with the upright 67 fixed in the aileron 49. The third arm 68 of the lever 59 is connected by a universal joint with a link 69 pivotally connected at its other end with an upright 70 fixed in the aileron 50. It will be observed that the arm 64 lies to the right hand of the pivot point of the lever 56 and that the arm 68 lies to the left hand of the pivot point of the lever 59.

The reason for this is that when turning movements are imparted to the levers 56 and 59 through the rod 53, the arms 64 and 68 will move in opposite directions so that the ailerons 49 and 50, with which they are respectively connected, will be turned in opposite directions. That is to say, by a clockwise movement imparted to the lever 56, the aileron 49 will be depressed; whereas the aileron 50 will be raised by the clockwise movement imparted to the lever 59. Both the arm 64 and the arm 68 are jointed so as to have a vertical swing relatively to the plane in which the other two arms of the levers 56 and 59 swing. It will now be clear that if the rod 53 is moved in a right hand direction to impart a clockwise turning movement to the levers 56 and 59, thereby moving the arm 64 rearwardly and the arm 68 forwardly, the ailerons 47 and 49 will be presented at a positive angle and the ailerons 48 and 50 will be presented at a negative angle. This will effect a lifting of the left hand end of the flying machine and a depressing of the right hand end thereof. If the rod 53 is moved in a left hand direction, the anti-clockwise movements imparted to the levers 56 and 59 will turn the ailerons 47 and 49 to negative angles and the ailerons 48 and 50 to positive angles. As the ailerons 49 and 50 turn both up and down the angular relation of the arms 64 and 68 change with respect to the other two arms of the levers 56 and 59.

The lateral movements are imparted to the rod 53 by the equilibrating mechanism in the same manner that the longitudinal movements are imparted to the rod or link 22. For this purpose an auxiliary pendulum 72 (Fig. 9) is mounted at 73 on the fuselage of the flying machine so as to swing laterally. When the lateral equilibrium of the flying machine is disturbed, the auxiliary pendulum 72 contacts with either the terminal 74 (Fig. 7) or the terminal 75 thereby effecting a closure of either one of the circuits in which the battery 79 is placed, so that the battery 79 may energize either the magnet 81 or the magnet 82 (Fig. 6) which are carried by horizontal shelves 83 and 84 respectively, fixed to the main pendulum 15. The magnets 81 and 82 act respectively upon the armatures 85 and 86 carried by the horizontally disposed arms of a three-armed lever 87 pivoted at 88. The vertically disposed arm 89 of the three-armed lever 87 is bifurcated at its upper end so as to straddle a collar 90 fastened to the rod 53. The bifurcated end of the arm 89 is provided with two rolls 91 which are engaged by a groove 92 formed in the collar 90 so that there may be a relative movement between the arm 89 and the collar 90 as the rod 53 is moved laterally by the swinging movements of the arm 89. When the left

hand end of the flying machine, as seen in the drawings, is depressed, the auxiliary pendulum contacts with the terminal 75 and this results in an energization of the magnet 82 so that the armature 86 is pulled toward it thereby imparting a movement to the lever 87 in a clockwise direction to move the rod 53 in a right hand direction. The right hand movement of the rod 53 effects, 10 as before explained, the turning of the ailerons 47 and 49 to a positive angle and the turning of the ailerons 48 and 50 to a negative angle. The pivot point 88 about which the lever 87 turns is the pivot point 15 about which the main pendulum 15 swings laterally relatively to the flying machine. When either armature 85 or 86 is drawn toward its respective magnet, the main pendulum is thereby rigidly connected with 20 the lever 87 so that when after the flying machine has tilted sidewise the main pendulum has had time to assume its vertical position, the ailerons will be turned proportionately to the change in the angular 25 relation between the vertical axis of the main pendulum and the lateral axis of the flying machine. The circle in dot and dash lines in Fig. 6 indicates the position that the main pendulum is seeking to attain. 30 Inasmuch as the lever 87 is rigidly connected with the main pendulum through the magnet 82, a movement in a right hand direction is being imparted to the rod 53 by the main pendulum to turn the ailerons 47 and 49 to a still greater positive angle and the ailerons 48 and 50 to a still greater negative angle. As the machine rights itself laterally in response to the positions of the ailerons, the rod 53 will be moved in a left 40 hand direction because then the main pendulum 15 will move toward the position indicated by the larger dotted circle. If the right hand end side of the flying machine is depressed, the movements of the parts will be the reverse of what they are when the left hand side of the machine is depressed. In this case the auxiliary pendulum by contacting with the terminal 84 causes the energization of the magnet 81 so 45 that the armature 85 will be drawn toward it to move the rod 53 in a left hand direction, thereby moving the ailerons 47 and 49 to be presented at a negative angle and the ailerons 48 and 50 to be presented at a positive angle. For the sake of convenience of illustration, the auxiliary pendulum 72 for controlling the lateral equilibrium of the machine and the auxiliary pendulum 16 for controlling the longitudinal equilibrium of 50 the machine have been shown as separate members. It will be understood, however, that only one auxiliary pendulum is necessary to make and break the contacts with the four terminals. In this case it would 55 swing from two axes disposed at right angles to each other, one axis being longitudinal and the other lateral.

Inasmuch as the main pendulum 15 serves to actuate both the horizontal rudder 19 by which the longitudinal stability of the flying machine is controlled and also the lateral rudders or ailerons by which the lateral stability of the machine is controlled, the main pendulum is mounted to have a fore and aft and a lateral swinging movement. In order that the main pendulum may swing freely in these directions it may conveniently be mounted in gimbal rings in the same manner that a mariner's compass is mounted. 60 This manner of mounting the main pendulum is shown particularly in Figs. 10 to 13 inclusive. The gimbal ring 95 is provided with trunnions 96 which are adapted to be received in bearings or journals fixed in the fuselage of the flying machine. Disposed at right angles to the axis of the trunnions 96 is a stud 97 fixed in standards rising from the gimbal ring 95. The main pendulum is provided with upright ears 98 in the upper ends of which are holes 99 to fit loosely on the stud 97. With this construction it will be clear that when the flying machine is tipped longitudinally, the main pendulum and the gimbal ring 95 will turn about the trunnion 96 as a pivot point relatively to the longitudinal axis of the flying machine. In reality, of course, it is the pendulum which tends to remain in its normal position with its vertical axis perpendicular and the flying machine which turns about the trunnion 96 relatively to the pendulum. On the other hand, when the flying machine is tipped laterally the gimbal ring 95 moves with the flying machine and in this case the pendulum swings on the longitudinal stud 97 or 65 rather the vertical axis of the pendulum tends to remain on a perpendicular dropped from the stud 97, and the flying machine tips laterally about the stud 97 as a pivot point. 70

The connections between the main pendulum and the horizontal rudder 19 on the one hand and the main pendulum and the ailerons on the other hand are shown more or less diagrammatically in Figs. 1 to 9, to illustrate the manner in which the auxiliary 75 pendulum and the main pendulum act upon the guiding devices. Figs. 10 to 13 show more fully the construction by which the main pendulum is enabled to act upon the guiding devices. The horizontal arms 26 and 28 of the three-armed lever 25 are provided with depending bosses 101 in which the pivot pin 23 is held fast. The forward end of the rod 22 is loosely connected with a pin 102 (Fig. 13) which passes through 80 the upper end of the bifurcated arm 24 of the lever 25. The pivot pin 23 is loosely received in holes in the upper ends of the lugs 103 and 104 rising respectively from the 85 horizontal arms 83 and 84 which carry the 90

100 105 110 115 120 125 130

magnets 81 and 82. The arms 83 and 84 are held in fixed relation with the main pendulum by pins 106 which pass through registering holes in the ears 98 and in the uprights 107 rising from the arms 83 and 84. The upper ends of the uprights 107 loosely embrace the stud 97. The three-armed lever 87 pivots on the stud 97.

When the flying machine is started in flight, it usually runs along the ground until it attains the requisite speed for rising into the air. The weight of the main pendulum is such that upon the starting up of the flying machine its inertia will, of course, tend to maintain it in its original position and, therefore, the angular relation between the main pendulum and the flying machine will be changed so that the rear magnet will strike its armature and thereby tilt the three-armed lever 25 to impart a turning movement to the rudder 19 in a direction to depress the nose of the machine. In order to obviate this premature depressing of the machine, the main pendulum is held in fixed relation with the flying machine as it starts in flight and until it attains a predetermined speed. This is accomplished by means of a latch device comprising a latch 110 pivoted on the transverse axle 111 upon which the wheels 112 are mounted. The upper or hook end 113 of the latch 110 enters a transverse recess 114 formed in the bottom of the main pendulum. A spring 116 tends to disengage the latch from the recess 114. The latch is held in the recess 114 by a spring-pressed finger 117 pivoted on the axle 111 and in fixed relation with a downwardly depending board 118 which is provided with hubs 119 loosely mounted on the axle 111. The construction and arrangement of these parts is such that until the flying machine attains the predetermined speed, the latch 110 is held in the recess 114 and the main pendulum is thereby held in fixed relation with the flying machine, but when the flying machine attains a predetermined speed, the air pressure against the board 118 is such as to turn it, thereby disconnecting the finger 117 from the latch and permitting the spring 116 to move the latch out of the recess 114 so as to permit the pendulum to move relatively to the flying machine.

The flying machine to which the equilibrating mechanism is shown as applied is of the self-propelled and self-controlled type for carrying a charge of explosive mixture and projectiles to a predetermined point where it is detonated. One feature of the invention accordingly is to adapt the main pendulum, by which the guiding devices are controlled to maintain the equilibrium or stability of the flying machine while it is pursuing its course to the predetermined point where the detonation of the charge is scheduled to take place, as a chamber or

shrapnel shell for receiving the explosive mixture and projectiles. The main pendulum is thus made to serve a double function, first the function of controlling the equilibrium of the machine and second the function of serving as the chamber for the explosive mixture. This conduces to compactness of structure and a more positive and certain control of the guiding devices while the machine is in flight, by concentrating the weight of the heavier parts of the machine as near to the center of gravity as possible. The explosive mixture and projectiles are indicated as contained within the main pendulum in Figs. 6, 9 and 14. When the flying machine has reached its destination or has been in flight for a predetermined length of time, the charge of explosive mixture may conveniently be detonated by any usual or preferred form of detonating mechanism, one form of which is diagrammatically illustrated at 121 in Fig. 14. The detonating mechanism 121 is in a circuit 122 which is normally open. The detonating mechanism operates to close the circuit when the flying machine has been in flight a predetermined length of time, and then the battery 123 energizes the solenoid 124, thereby breaking the contact between the armature 125 and the terminal 126. This serves to break the circuit 128 in which a battery 129 is located, so that the latter no longer energizes the solenoid 130. Thereupon a hammer 131 normally held up by the solenoid 130 drops upon a cap or fuse 132 detonating the charge of explosive mixture.

Although in the illustrated embodiment of the invention the equilibrating mechanism has been shown as applied to a self-propelled and self-controlled flying machine, it will be understood that the equilibrating mechanism of the present invention is equally well adapted for application to other types of machines than flying machines and in particular to a flying machine which is primarily controlled by an aeronaut.

Having thus described the invention what is claimed is:

1. An equilibrating mechanism for flying machines comprising a guiding device, a lever connected with the guiding device, a main pendulum normally disconnected from the lever, a magnet carried by the pendulum, an armature carried by the lever, a battery in a circuit normally open, and an auxiliary pendulum adapted when the equilibrium of the flying machine is disturbed to close the circuit so as to energize the magnet to turn the lever and thereby impart a primary restoring movement to the guiding device, the energizing of the magnet serving to connect the lever with the main pendulum so that the guiding device is thereafter turned proportionately

to the change in the angular relation between the main pendulum and the flying machine.

2. An equilibrating mechanism for flying machines comprising guiding devices, operating means therefor, a main pendulum normally disconnected from the guiding device operating means, but which when connected therewith serves to turn the guiding devices proportionately to a change in the angular relation between the main pendulum and the flying machine, and an auxiliary pendulum for imparting a primary restoring movement to the guiding devices when the equilibrium of the flying machine is disturbed.

3. An equilibrating mechanism for flying machines comprising guiding devices, a pendulum normally disconnected from the guiding devices, an auxiliary device, and means through which when the equilibrium of the machine is disturbed a primary restoring movement is imparted to the guiding devices through the action of the auxiliary device and they are thereby connected with the pendulum to be thereafter moved proportionately to the amount of angular change between the pendulum and the flying machine.

4. An equilibrating mechanism for flying machines comprising guiding devices, operating means therefor, a main pendulum normally disconnected from the guiding device operating means, an auxiliary pendulum, and a solenoid interposed between the main pendulum and the guiding device operating means adapted to be energized through the action of the auxiliary pendulum to connect the two when the equilibrium of the flying machine is disturbed.

5. An equilibrating mechanism for flying machines comprising a horizontal rudder, operating means therefor, a main pendulum, an auxiliary pendulum, and means for causing the rudder operating means to move the rudder when the auxiliary pendulum changes its angular relation with the flying machine to thereby connect the main pendulum with the rudder operating means so as to turn the rudder proportionately to the change in the angular relation between the main pendulum and the longitudinal axis of the flying machine.

6. An equilibrating mechanism for flying machines comprising lateral rudders or ailerons located on opposite sides of the flying machine, a system of levers connected with the ailerons in such manner that when the levers are turned in the same direction the ailerons on one side of the machine are moved in one direction and the ailerons on the other side of the machine are moved in the opposite direction, a main pendulum normally disconnected from the levers, an auxiliary pendulum and means through

which the auxiliary pendulum acts when the lateral equilibrium of the machine is disturbed to impart a primary restoring movement to the ailerons and to thereby connect the main pendulum with the levers.

7. An equilibrating mechanism for flying machines comprising guiding devices, a main pendulum, means interposed between the main pendulum and the guiding devices through which the guiding devices are turned proportionately to the change in angular relation between the main pendulum and the flying machine, a mounting for the main pendulum so that it may swing both fore and aft and laterally, magnets carried by the main pendulum for connecting it with the means interposed between it and the guiding devices, and an auxiliary pendulum acting when the equilibrium of the machine is disturbed to close a circuit and thereby energize certain of the magnets.

8. An equilibrating mechanism for flying machines comprising a pendulum, means for holding the pendulum in rigid connection with the flying machine, and means for automatically releasing the holding means when the flying machine has attained a predetermined speed whereupon the pendulum is free to move relatively to the flying machine.

9. An equilibrating mechanism for flying machines comprising a guiding device, operating means therefor, a pendulum for controlling the guiding device operating means, means for holding the pendulum and the flying machine immovable relatively and means for automatically releasing the holding means when the flying machine attains a predetermined speed.

10. An equilibrating mechanism for flying machines comprising a guiding device, operating means therefor, a pendulum for controlling the guiding device operating means, a latch for holding the pendulum in rigid connection with the flying machine, and means for automatically disconnecting the latch from the pendulum when the flying machine has attained a predetermined speed.

11. An equilibrating mechanism for flying machines comprising means operable after a time interval following the displacement of the flying machine from a condition of equilibrium to restore the machine to equilibrium, and means tending to restore the machine to equilibrium before the operation of the said restoring means.

12. An equilibrating mechanism for flying machines comprising a guiding device, a relatively heavy pendulum adapted to operate upon the guiding device after a time interval following the displacement of the machine from a condition of equilibrium to restore the machine to equilibrium and a relatively light pendulum adapted to oper-

ate upon the guiding device to tend to restore the machine to equilibrium before the operation of the relatively heavy pendulum.

13. An equilibrating mechanism for flying machines comprising a guiding device, a relatively heavy pendulum adapted to operate upon the guiding device after a time interval following the displacement of the machine from a condition of equilibrium to restore the machine to equilibrium and a relatively light pendulum adapted to operate upon the guiding device to tend to restore the machine to equilibrium before the operation of the relatively heavy pendulum, and means whereby the operation of the relatively light pendulum renders the relatively heavy pendulum operative.

14. An equilibrating mechanism for flying machines having, in combination, a guiding device, means operable upon a displacement of the flying machine from a condition of equilibrium for controlling the position of the guiding device in accordance with the degree of displacement of the machine from equilibrium to effect a restoration of the machine to equilibrium with a force which gradually decreases to zero as the equilibrium of the machine becomes gradually restored, and means for compensating for the lack of control over the guiding device during the displacement of the machine from equilibrium to the predetermined degree of displacement.
